Patented Feb. 19, 1963

194,642

PORTABLE AUTOGRAPHIC REGISTER

Russell Katz, Hamilton, Ohio, assignor to Krauth & Benninghofen, Hamilton, Ohio, a partnership

Filed Sept. 17, 1962, Ser. No. 71,731

Term of patent 14 years

(Cl. D64—11)

Fig. 1

Fig. 2

Fig. 3

Fig. 1

Fig. 2

I claim:
The ornamental design for a portable autographic register, substantially as shown.
